GAS-WASHER.

1,112,381.

Specification of Letters Patent.

Patented Sept. 29, 1914.

Application filed February 10, 1912. Serial No. 676,874.

To all whom it may concern:

Be it known that I, JOHANN F. M. PATITZ, a citizen of the United States, residing at Milwaukee, in the county of Milwaukee and 5 State of Wisconsin, have invented a certain new and useful Improvement in Gas-Washers, of which the following is a specification.

This invention relates to improvements in the construction of gas purifiers or washers.

10 The object of the invention is to provide a gas washer which is simple in construction and efficient in operation and in which the impure gas is successively subjected to contact with films and sprays of water, the impurities being removed by cleaning water of 15 different purity as it flows in a direction opposed to that of the gas.

A clear conception of one embodiment of the invention can be had by referring to the 20 drawing accompanying and forming part of this specification, in which like reference characters designate similar parts.

The single figure of the drawing discloses a central vertical section through a gas 25 washer showing fragments of the inlet and discharge pipes leading to and from the casing of same.

The casing 13 is provided with an inlet 33 near its lower end and a discharge 6 at the 30 upper end thereof. The lower end of the casing 13 is provided with a water seal 34 which serves as a packing for the lower end of the casing. The cap 5 incloses the upper end of the casing 13 and forms a support 35 for the bearing frame 4. The rotor or fan shaft 1 is mounted concentrically in the bearing frame 4 and casing 13, being vertically supported by means of a thrust bearing 3 formed in the bearing frame 4. The 40 drive pulley 2 is fixed to the upper extremity of the shaft 1 and is adapted to receive rotary motion from a motor by means of a belt, not shown.

The fan supporting member 29 is fixed to 45 the lower extremity of the shaft 1 and carries a series of outwardly projecting fan plates 7, 17, 27. The blades 8, 18, 28, are attached to the plates 7, 17, 27, respectively, and project radially from the axis of the 50 shaft 1. The blades 8, 18, 28, may, however, be of spiral formation and not flat radial plates as disclosed, but it is desirable to have the inlet edge of each blade extend across the entire width thereof. The lower end of the 55 blades 8, 18, 28, are secured to baffle plates

10, 110, 210, which are formed with large circular inlet openings adjacent the supporting member 29. These fan plates 7, 17, 27, and baffle plates 10, 110, 210, inclose the blades 8, 18, 28. The inlet 30 of the lower 60 fan connects directly with the inlet 33 to the casing 13. The plates 7, 17, 27, have upper plane surfaces and constitute means having circularly continuous surfaces adjacent their peripheries.

The casing 13 is provided with angular inwardly and downwardly projecting baffle plates 11, 39, which approach but have central openings which are slightly larger in diameter than the peripheries of the baffle 70 plates 10, 110, respectively. As the thrust bearing 3 is formed of a series of plates, the opening existing between the baffle plates 10, 110, and the baffle plates 11, 39, respectively, can be varied by either inserting or removing bearing plates at the thrust bearing 3. The fan rotor may be bodily removed from above through the central openings in the plates 11, 39, by removal of the cap 5. Nozzles 9 which receive their supply of water 75 from supply pipes 12, are directed inwardly to the spaces formed between successive fans. The nozzles 32, which are supplied with water through the pipe 31, are directed toward the interior of the lower fan, these 80 nozzles 32, however, being unessential. The lower end of the casing 13 is formed with circular recesses 35, 36, which are adapted to receive or collect the downwardly flowing water injected through the nozzles 9, the 85 water being carried from these recesses 35, 36, through the pipes 37, 38, to the water seal 34.

During the operation of the washer, the shaft 1, supporting member 29, and the fans 90 are given a rapid rotary motion by means of power applied to the pulley 2. The impure gas is drawn through the inlet 33 and suction opening 30 to the interior of the first or lower fan by the fan action of the 100 blades 28. Water is injected to the interior of the casing 13 through the nozzles 9 and flows from the upper or first set of nozzles 9 onto the fan plate 17 of the middle fan. The action of centrifugal force causes the 105 water thus thrown upon the plate 17 to be thrown outwardly in the form of a film or thin sheet, so that after leaving the plate 17 it impinges upon the adjacent inner surface of the casing 13. The water thus de- 110

posed upon the interior wall of the casing 13 flows down the wall and over the baffle plate 39, from which it flows through the annular space between the baffle plate 110 and the plate 39, to the fan plate 27 of the first or lower fan. Additional water is admitted to the upper surface of the fan plate 27 through the lower or second series of nozzles 9. The water thus deposited upon the plate 27 is thrown outwardly in the form of a film, by centrifugal force and impinges against the inner wall of the casing 13. Upon striking the walls of the casing 13, the water flows downwardly into the recess 36. Since the amount of water admitted to the washing chamber by the nozzles 9 is too great to pass directly through the overflow pipe 38, the water rises to a point somewhat above the top of the partition separating the recess 35 from the recess 36, thus also filling the recess 35. The gas discharged from the fan blades 28 causes the upper surface of the excess water above the recess 36 to gradually slope toward the outer wall of the casing 13, the angle of slope of this surface being regulable either by variation in the amount of water admitted to the casing 13 through the nozzles 12, 32, or by vertical adjustment of the fan rotor 30 whereby the size of the annular opening between the plate 210 and the adjacent partition may be varied. As the impure gas is discharged by centrifugal force from the first fan blades 28, it strikes the upper surface of the water flowing into the recess 35, and on account of the inclination of this surface of water, is directed upwardly. The rotary motion of the blades 18 of the second fan produces a suction or reduced pressure in the space between the plate 110 and the plate 27, thus causing the gas discharged from the blades 28 of the first fan, to pass through the film of water discharged from the fan plate 27, to the space between the lower and intermediate fans. In this space the gas is directly subjected to the spray emanating from the second series of nozzles 9. The gas then passes to the interior of the second or intermediate fan from whence it is drawn by the blades 8 and is discharged against the sheet of water which flows down the inclined plate 39. On account of the inclination of the baffle plate 39, the gas is directed upwardly, thus passing in direct contact with the sheet or film of water which flows down the walls of the casing 13 and the plate 39. The reduced pressure in the space between the upper and intermediate fans caused by the rotation of the fan blades 8, draws the gases discharged from the blades 18 toward the inlet of the upper fan. In its passage the gas is drawn through the film of water discharged outwardly by the fan plate 17, and is further subjected to the sprays of water emanating

from the nozzles 9. Upon being discharged from the blades 8, the cleaned gas passes directly through the discharge 6 to the storage reservoir or gas engine. It will thus be seen that the gas after having been drawn into the lower fan, is subjected to the successive actions of flowing and sprayed waters in the successive fan chambers, thereby removing all impurities and permitting the discharge of purified gas through the discharge 6. The formation of the plates 7, 17, 27, with circularly continuous surfaces adjacent their peripheries, permits the water leaving the periphery of each of these plates to form a continuous uniform film. The means for vertically adjusting the fans to adjust the passages between the baffle plates 10, 110, and the plates 11, 39, permits the piling up of water to any desired degree adjacent the peripheries of the fans, thus giving a simple means for regulating the amount and purity of the water suspended within the washer. Due to the fact that direct impact of the fan blades against the gas is avoided, the power required for rotating the fans is also reduced to a minimum. 90

It should be noted that during its passage through the washer, the impure gas is gradually subjected to the cleaning action of water of different purity, that is to say, the gas having the greatest amount of impurities is brought in contact with the impure water while the relatively clean gas receives its final washing with water which is free from impurities. It is, moreover, not essential to subject the gas to only two cleaning stages as disclosed, since any number of these successive stages could be incorporated. 95

It should be understood that it is not desired to be limited to the exact details of construction shown and described, for obvious modifications will occur to a person skilled in the art. 100

It is claimed and desired to secure by Letters Patent, 110

1. In a gas washer, a casing, means for admitting liquid spray to said casing, means having a circularly continuous surface adjacent its periphery for collecting said spray and for directing said liquid outwardly toward the wall of said casing in the form of a film, means for directing said film of liquid inwardly away from the wall of said casing, and inclosed fan blades located between said outwardly and said inwardly directing means for forcing the gas through the casing whereby the gas flows against and through said film and said spray in succession. 115

2. In a gas washer, a casing, means for admitting liquid to said casing, means having a circularly continuous surface adjacent its periphery for directing said liquid outwardly toward the wall of said casing in 120

125

130

the form of a film, means for directing said film of liquid inwardly away from the wall of said casing, and inclosed fan blades located between said outwardly and said inwardly directing means for forcing the gas through the casing whereby the gas flows against and through said film in succession.

3. In a gas washer, a casing, means for directing liquid toward the mid portion of 10 said casing, means having a circularly continuous surface adjacent its periphery for collecting and directing said liquid to flow toward the wall of said casing in the form of a film, means for reversing the direction 15 of flow of said liquid film, and means located between said film directing and reversing means for gradually forcing gas first along and then through said liquid.

4. In a gas washer, a casing, rotary means 20 within said casing, means for admitting liquid to said casing and for directing said liquid toward said rotating means, means carried by said rotary means and having a circularly continuous surface adjacent its 25 periphery for collecting and directing said liquid to flow outwardly toward said casing in the form of a continuous film, means for reversing the direction of flow of said liquid film, and means carried by said rotating 30 means for gradually forcing gas successively along and through said film.

5. In a gas washer, a rotatable fan, blades in said fan, said fan blades having their entire inlet and discharge edges radially directing, means for admitting gas to the inlet 35 end of said fan blades, and means having a circularly continuous surface adjacent its periphery for forming a continuous inclosing film of liquid at the discharge of said fan.

6. In a gas washer, a casing, a series of baffle plates within said casing, said plates having alined openings therein, and a fan rotor mounted within said casing and removable upwardly through said openings 45 without displacement of said casing.

7. In a gas washer, a casing, a series of baffle plates within said casing, said plates having alined openings therein, and a fan rotor mounted within said casing and adjustable relative to said baffle plates, said rotor being removable upwardly through said openings without displacement of said casing.

In testimony whereof, the signature of 55 the inventor is affixed hereto in the presence of two witnesses.

JOHANN F. M. PATITZ.
